UNITED STATES PATENT OFFICE.

CHARLES A. HUSSEY, OF NEW YORK, N. Y., ASSIGNOR, BY MESNE ASSIGNMENTS, TO THE ELECTRIC COMPANY, OF SAME PLACE.

MEANS FOR VARYING LIGHT FOR INCANDESCENT ELECTRIC LAMPS.

SPECIFICATION forming part of Letters Patent No. 546,666, dated September 24, 1895.

Application filed September 29, 1893. Serial No. 436,838. (No model.)

To all whom it may concern:

Be it known that I, CHARLES A. HUSSEY, of the city, county, and State of New York, have invented a certain new and useful Improvement in Means for Varying Light for Incandescent Electric Lamps, of which the following is a specification.

I will describe an incandescent electric lamp embodying my improvement, and then point out the novel features in a claim.

In the accompanying drawings, Figure 1 is a side view of an electric-lamp holder fitted with an electric lamp and comprising my improvement. Fig. 2 is a central vertical section of the lamp-holder. Fig. 3 is a central vertical section taken in a plane at right angles to that of Fig. 2. Fig. 4 is a horizontal section in the plane of line 4, Fig. 2. Fig. 5 is a horizontal section in the plane of line 5, Fig. 3. Fig. 6 is a diagrammatic view illustrating the circuit.

Similar letters and numerals of reference designate corresponding parts in all the figures.

25 A designates a head, which may be made of metal, and, as here shown, is of circular form. It is shown as provided with a centrally-located and upwardly-extended tubular portion a, which may advantageously be 30 screw-threaded for attachment to a fixture, but which in the present instance simply serves to permit the passage of insulated electric-circuit wires B' B² through it. This head is provided with a flange a' on its outer 35 edge, and, as here shown, this flange is externally shouldered to receive a cylindric shell A'. The shell A' may be made of metal.

The shell A' at the end which is distant from the head A is shown as being contracted 40 into a tubular portion a². It has fitted into its extremity a bushing A² of insulating material, the latter being provided with a cylindric body entering the shell and also with a shoulder which extends across the extremity 45 of the shell. This bushing is internally screw-threaded to engage with a socket C. This socket is made of metal and is screw-threaded externally and internally. This socket is connected through intermediate parts with 50 the head A and the bushing A², and with it

secures the bushing and also the shell A' in place.

D' D² designate disks of insulating material, which, for instance, may be composed of a number of sheets of mica laid one upon the other. Preferably these disks are of a size to bear against the interior of the shell A. The disk D' is fastened to a block or bar E of insulating material, and the latter is secured to the head A by screws e' e² through the head 60 and into the ends of the bar. These screws e' e² are shown as extending through the shoulder portion of the head. The shell A' will have notches in its edge, so as to pass over these screws. The latter will then serve 65 as a means for preventing the rotation of the shell.

Between the disks D' D² a bar D extends. This is made of metal and is shown as having the ends shouldered or tenoned, so as to fit 70 into holes provided in the central portions of the disks. Screws d' d² serve to secure the ends of the bar D to the disks. The screw d' is shown as passing through the bar E, as well as through the disk D' and into the bar 75 D. The screw d² passes through a block F of insulating material. It may advantageously be of circular form. The screw d² screws the block F in place. I may here remark that the socket C is fastened to the block F. As 80 here shown, the socket C is provided with a flange at its inner end, and is secured in place by screws fastened through this flange. One of such screws may merely pass into the block F. The other screw f' passes through 85 the block F, through the disk d², and into a binding-post f², the engagement of the screw and binding-post serving to clamp together the parts which are intermediate of the binding-post and the head of the screw, 90 and also to establish electrical contact between the binding-post and the socket C.

G' G² G³ G⁴ designate resistance devices, here shown as made in the form of pencils. They may be advantageously made of composition of good conducting material and a poor conducting material—such, for instance, as graphite and peroxide of manganese. They may be mixed in a powdered condition, and after mixing the composition may be 95 100

forced through a die. These pencils are of cylindric form, and at the ends they fit in cups g , the latter being shouldered or tenoned so as to fit in holes with which disks $D' D^2$ 5 are provided, and being fastened in place by screws g' . As here shown, plates g^2 are interposed between the heads of the screws g' and the disks $D' D^2$, these plates being made of metal and serving, in connection with the 10 heads of the screws, to clamp circuit-wires, and so establish communication between the resistance devices.

H designates a piece of insulating material arranged between the disks $D' D^2$. It may 15 be made of any suitable insulating material, and may advantageously be made of a number of sheets of mica, here shown as being made of segmental form.

H' designates a rotary metallic shaft having at one end a thumb-piece or key H^2 of insulating material, the latter being extended through the cylindric shell a' . This shaft H' is fitted in a bearing formed in the bar D , so as to be free to rotate or oscillate. As here 20 shown, a bearing is provided by inserting a sleeve d transversely into the bar D , for thus a very long and serviceable bearing can be given to the shaft. The oscillation of the shaft is limited by means of a pin h extending 25 radially from it and coacting with shoulders formed at one end of the sleeve d , these shoulders being obtained by notching the end of the sleeve.

The shaft H' is provided with a metallic finger H^3 , and the side of the piece H which is adjacent to this finger is provided with a number of contact buttons or pieces $h' h^2 h^3$ 30 $h^4 h^5 h^6$. These may consist of metal cylinders externally shouldered or tenoned, so as to fit into holes in the pieces H , and when so made they can be conveniently secured in place by means of screws h^7 , extending from the opposite side of the piece H in the tapped holes in these buttons or contact-pieces. The 35 heads of the screws may also serve as a means for connecting wires to establish electrical communication. The buttons or contact-pieces, of course, are arranged in an arc-shaped row concentric with the shaft H' .

The cylinder A' is provided with a long notch opposite the shank of the thumb-screw or key H^2 , and to fill this notch I preferably attach to the head A a strip of metal a^5 , fastened to the shoulder portion of the head A 40 by means of a screw a^6 .

J designates a block of metal fastened by screws $j' j^2$ to the block F of insulating material, said block J being arranged inside of the socket C .

The circuit connections may best be understood by reference to Fig. 6. The wire B' 45 connects with the bar D , and hence is in electrical communication, through the sleeve d and shaft H' , with the finger H^3 . While the 50 lamp is not in use this finger rests upon the contact-piece h' , and as this is unconnected with any other metallic part of the lamp no

current then proceeds to the lamp. By oscillating the thumb-piece or key H^2 the finger H^3 may be adjusted onto either of the contact-pieces $h^2 h^3 h^4 h^5 h^6$. From the contact-piece h^2 a wire 1 extends to the screw g' . 55

From the resistance device G' the circuit is continued by plate g^2 to one end of the resistance device G^2 . Thence it is extended along 60 another plate g^2 to one end of the resistance device G^3 . Thence it is continued along another plate g^2 to one end of the resistance device G^4 . From the latter it is continued by 65 wires 2 and 3 to the block J , which is within 70 the socket C .

From the contact-piece h^3 a wire 4 extends to that plate g^2 which extends between the resistance devices $G^2 G^3$. The resistance G' , therefore, will be cut out of the circuit previously 75 described whenever the finger H^3 is shifted onto the contact-piece h^3 .

From the contact-piece h^4 a wire 5 extends to that plate g^2 which extends between the resistance devices $G^2 G^3$. Hence when the 80 finger H^3 is shifted onto the contact-piece H^4 the resistance devices $G^2 G^3$ will be cut out of the circuit. The wire B^2 communicates with the screw f' and hence with the socket C .

A wire 6 extends from the contact-piece h^5 85 to the resistance device G^4 . Hence when the finger H^3 is adjusted onto the contact-piece h^5 the resistance devices $G^2 G^3 G^4$ will be cut out of circuit.

From the contact-piece h^6 a wire 7 extends 90 to the wire 3. Hence when the finger H^3 is adjusted onto the contact-piece h^6 all the resistance devices $G' G^2 G^3 G^4$ will be cut out of circuit.

By cutting out or introducing resistance 95 devices through the agency of the oscillating finger 3 the current may be varied, so as to increase or decrease the light from the lamp.

By my improvement I produce a very simple, cheap, and efficient contrivance for varying the light of an incandescent lamp.

What I claim as my invention, and desire to secure by Letters Patent, is—

In an electric lamp holder, the combination 100 of a socket or receptacle, two electrodes, connections for leading in wires or conductors, two disks of non-conducting material, resistance devices in the form of rods or pencils extending between and connected to said disks, a block or plate interposed between 105 said disks, a row of contact pieces in electrical communication with said resistance devices, and a key journaled in said plate or block and provided with a finger adapted to coact with said set of insulated contact pieces, 110 substantially as specified.

In testimony whereof I have signed my name to this specification in the presence of two subscribing witnesses.

CHAS. A. HUSSEY.
